UNITED STATES PATENT OFFICE

160,347

FRONTPIECE FOR A HAIR ORNAMENT

Nathan L. Solomon Englewood, N. J.

Application April 8, 1950, Serial No. 9,055

Term of patent 14 years

(Cl. D86—10)

To all whom it may concern:

Be it known that Nathan L. Solomon, a citizen of the United States, residing at 343 Highview Road, Englewood, county of Bergen, and State of New Jersey, has invented a new, original, and ornamental Design for a Frontpiece for a Hair Ornament, of which the following is a specification, reference being had to the accompanying drawing, forming part thereof.

In the drawing:

Fig. 2 is a side elevation of the ornament.

I claim:

The ornamental design for a frontpiece for a hair ornament, substantially as shown.

NATHAN L. SOLOMON.
